UNITED STATES PATENT OFFICE.

FRED EUGENE BRIGHT, OF PHILADELPHIA, PENNSYLVANIA, ASSIGNOR
TO MERGENTHALER LINOTYPE COMPANY, A CORPORATION OF NEW
YORK.

LINOTYPE-MACHINE.

No. 832,769.

Specification of Letters Patent.

Patented Oct. 9, 1906.

Application filed May 29, 1905. Serial No. 282,871.

To all whom it may concern:

Be it known that I, FRED EUGENE BRIGHT, a citizen of the United States, and a resident of the city of Philadelphia, in the county of Philadelphia and the State of Pennsylvania, have invented certain new and useful Improvements in Linotype-Machines, of which the following is a specification.

My invention relates to linotype-machines designed to produce printing-forms composed of linotypes—namely, line bars or slugs—each bearing on its face properly justified all of the characters which appear in a line.

15 The machine is of the same general type as that illustrated and described in my Letters Patent No. 793,766, July 4, 1905, and may be regarded as an improvement thereon. In order to show the relation of the various 20 parts, the machine is illustrated herein in its entirety; but for a description of the devices and operations common to both cases reference may be had to the before-mentioned patent.

25 Referring to the drawings, wherein the same parts are represented by the same letters and figures of reference throughout the several views, Figure 1 is a front elevation of the machine. Fig. 2 is a right side elevation. Fig. 2^a is a similar view, being a continuation of Fig. 2. Fig. 3 is a left side elevation, partly broken away to expose interior parts. Fig. 3^a is a similar view, being a continuation 30 of Fig. 3. Fig. 4 is a rear elevation. Fig. 5

35 is an enlarged plan view, partly in section, on the line 5 5 of Figs. 1 and 11. Fig. 5^a is a vertical section on the line 5^a 5^a of Fig. 5. Fig. 6 is a plan view similar to Fig. 5, showing the parts in somewhat different positions. Fig. 6^a is a sectional detail view. Fig. 7 is a plan view, partly in section, on the line 7 7 of Fig. 1. Fig. 8 is a vertical section taken substantially on the line 8 8 of Figs. 1 and 14. Fig. 9 is a partial vertical section taken substantially on the line 9 9 of Figs. 1, 10, and 14. Fig. 10 is a partial vertical section taken substantially on the line 10 10 of Fig. 9. Fig. 10^a is a perspective view of the matrix. Fig. 10^b is a perspective view of the spacer. Fig. 11 is a vertical section taken substantially on the line 11 11 of Figs. 1 and 14. Figs. 12 and 13 are similar views show-

ing certain of the parts in different positions. Fig. 14 is a horizontal section taken substantially on the line 14 14 of Figs. 1, 2, 3, 4, 8, 9, 55 11, and 15. Fig. 15 is a partial vertical section taken substantially on the line 15 15 of Figs. 1 and 14. Fig. 16 is a similar view showing certain of the parts in different positions. Fig. 16^a is a transverse vertical section of the mold and pot mouth. Fig. 17 is a rear view of a portion of the machine, certain of the parts being removed. Fig. 17^a is a vertical section of the spacer-elevator. Fig. 18 is a view similar to Fig. 17, but showing 60 parts in different positions. Fig. 18^a is a view similar to Fig. 17^a, but showing the spacer-elevator in its upper position. Fig. 19 is a detached detail view of certain of the parts shown in Figs. 17 and 18. Fig. 20 is a 65 vertical section of the keyboard, taken on the line 20 20 of Figs. 1 and 7. Fig. 21 is a sectional detail taken on the line 21 21 of Fig. 20. Figs. 22, 23, and 24 are views similar to Fig. 20, showing certain of the parts thereof in different positions. Fig. 25 is a vertical 70 section of the keyboard taken on the line 25 25 of Figs. 1 and 7. Fig. 26 is a plan detail of certain of the parts shown in Fig. 25. Fig. 27 is a diagrammatic view similar to Fig. 25 75 and showing the parts thereof in different positions. Fig. 28 is a perspective view of the trimming, ejecting, and slug-receiving means. Fig. 29 is an elevation of certain of these parts looking in the direction of the arrow 29 of Fig. 28. Fig. 30 is a sectional detail on the line 30 30 of Fig. 29. Fig. 31 is a sectional detail on the line 31 31 of Fig. 29. Fig. 32 is a left side elevation on an enlarged scale. Fig. 32^a is a sectional detail of the 80 elevator-gearing. Fig. 32^b is a detail of the jaw and elevator cams. Fig. 33 is a front view of the distributing and connected devices. Fig. 34 is a top view of the same. Fig. 35 is a rear view of the upper part of the machine. Fig. 36 is a right side elevation, on an 85 enlarged scale and partly in section, of the elevator and connected devices. Fig. 37 is a similar view showing the parts in different positions. Fig. 37^a is a detail view of certain 90 features of the elevator. Fig. 38 is a front view, on an enlarged scale, of the elevator in its uppermost position and the parts adjacent thereto. Fig. 39 is a diagrammatic 95 100

view illustrating the action of the connected devices for transferring the matrices from the elevator to the distributing means. Fig. 40 is a vertical section taken on the line 40 40 of Fig. 35. Fig. 41 is a sectional detail taken on the line 41 41 of Fig. 40. Fig. 42 is a sectional detail taken on the line 42 42 of Fig. 41. Fig. 43 is a perspective detail, partly in section. Fig. 44 is a sectional detail taken 10 on the line 44 44 of Fig. 45. Fig. 45 is a detached detail view. Fig. 46 is a vertical section taken on the line 46 46 of Fig. 45. Figs. 47 and 48 are details. Fig. 48^a is a detached view of the mold-turning cams, &c. Fig. 49 is a vertical sectional view of the spacer-magazine and adjacent parts. Figs. 50 and 51 are respectively front and side views of the spacer-magazine. Fig. 52 is a detached view of the spacer-escapement. Fig. 53 is a 20 view of a slug or linotype.

The general operation and construction of the machine, as before stated, are substantially the same as those described in the previous patent with the exception of the differences hereinafter described.

The pivotally-mounted delivery-chute D (see Figs. 1 and 49) is provided near the discharging-point with a movable tongue 505 and the connected button 507, whereby the 30 tongue may be turned into the assembling-channel I and caused to engage with the notch 506. In this position the tongue 505 serves the double function of holding the delivery-chute D in its operative position and 35 also of directing the matrices in their descent into proper position before the reciprocating pusher 35. The pusher 35 has the same function as the similarly-designated part in the previous patent, but is herein caused to reciprocate by the pitman 504, actuated by the 40 crank-disk 503, which receives its motion from the connected pulley 502, belt 501, and pulley 500 on the sleeve 369. (See Figs. 1, 2, 4, 5, 5^a, 6, and 7.) The keyboard mechanism is provided with a locking device (see 45 Fig. 20) in the form of a half-round shaft 508, which may be turned by the handle 509 (see Fig. 2) to engage or release the entire series of levers 4, as desired.

50 The spacer-magazine G is located with its discharging-point in proximity to that of the chute D. (See Figs. 49, 50, 51, and 52.) The spacers B are stored therein with their ears B' B' resting upon the sides of the magazine and the rails G' G' and with their lower portions B² B² against the abutments G⁴ G⁴. As shown in Fig. 49, the spacers in the magazine are inclined inwardly and away from the front side thereof, thus obviating the 55 necessity for confining their upper ends. The escapement-lever G³ is located between the abutments G⁴ G⁴ and when operated raises the outermost spacer B clear of the abutments and permits it to drop into the 60 assembling-channel I among the matrices A

in front of the reciprocating pusher 35, whereby the line is advanced as assembled. The escapement-lever G³ is mounted upon the rock-shaft G⁵, provided with the operating-arm G⁶. The necessary reciprocating motion is imparted to the arm G⁶ by a latch 3, which is a member of the regular keyboard mechanism, similar to that shown in Fig. 20. The outer extremity of arm G⁶ rests directly upon the top of its latch 3, (see Figs. 7 and 52,) and the latter is operated in the usual manner by the cylinder 11, its engagement therewith being controlled by the space-key H. (See Figs. 1, 2, 3, 7, and 20.) In Fig. 49 the escapement-lever G³ is shown in its inoperative position and in Fig. 51 in its operative position, having disengaged the spacer B, which is free to descend in the direction of the arrow into the line. When a spacer B is thus released, gravity causes the remaining ones to move forward and rest against the abutments G⁴ G⁴. The spacers B are delivered to the magazine G from the elevator J in the manner subsequently to be described, (see Figs. 18 and 18^a.) at which 85 time their ears B' B' rest upon the sides of the magazine G. They then move to the position shown in Figs. 49 and 50, with their ears B' B' resting upon the cut-away sides of the magazine G and the rails G' G'. A front piece G² is adjustably mounted upon the magazine G so as to guide the spacers in their descent and maintain them in proper position. The piece G² is cut away near its lowermost point to permit the free movement of 90 the spacer when acted upon by the escapement. 95

The yielding resistant which holds the line in position as it is advanced step by step by the reciprocating rod 35 consists of the 105 slide rod 44 and the finger 45 thereon. Normally the finger 45 occupies the position shown in Figs. 1 and 7 in the channel I and immediately in front of the assembling-point. As the line is composed and advanced 110 by the pusher 35 the finger moves to the position shown in Fig. 5, and when the line is transferred to the casting-point by the slide 43 it is withdrawn from the channel, as shown in Fig. 6. The sliding rod 44 has a 115 stud 510, which traverses the straight groove 511, and thereby holds the finger 45 in position within the channel I. The end of the rod 44 is provided with a projecting piece 512, connected to the rod by the spiral spring 514. (See Fig. 6^a.) The spring-pressed piece 512 rests against the stationary frame-piece 516, and the tendency of the spring 514 is to turn the rod 44 and withdraw the finger 45 from the channel I; but this pressure is 125 resisted by the engagement of the stud 510 with the straight groove 511. When, however, the transfer-slide 43 operates to move the assembled line to the casting position, the rod 44 is advanced therewith until the 130

stud 510 passes out of the straight groove 511 into the inclined way 513, thereby turning the rod 44 and withdrawing the finger 45 from the channel I, as shown in Fig. 6. The function of the spring 514 is twofold, as it serves to withdraw the finger 45 from the channel I when the stud 510 reaches the inclined way 513, and also causes the stud to bind slightly in the groove 511 as the rod 44 moves, and thus insures the necessary resistance to the advancing line.

The restoration of the rod 44 and finger 45 to their normal positions is effected by the return of the transfer-slide 43. When the slide moves forward to the position shown in Fig. 6, a spring-pressed pawl 521 thereon engages the projection 520 on the rod 44, and as the slide returns the rod moves therewith, and the stud 510 passes from the inclined way 513 to the straight groove 511, thus again inserting the finger 45 into the channel I in readiness for the assemblage of a new line. After the rod 44 and finger 45 have been restored to their normal positions the further retreat of the transfer-slide 43 brings the spring-actuated pawl 521 into engagement with the cam-surface 120, (shown in Fig. 1 and in dotted lines in Figs. 5, 6, and 7,) thus freeing the pawl from its engagement with the projection 520.

A pivoted blade 525 is also provided (see Figs. 5, 5^a, 6, 17, and 18) which projects beneath the corners of the matrices as they are being assembled (see Fig. 5) and serves as an additional vertically-acting support therefor. The blade 525 has a limited pivotal movement which is controlled by the stud 526 on the transfer-slide 43. When the latter is at rest, the stud engages the end of the blade 525 and holds it in the channel I and partly beneath the line, as shown in Fig. 5. When the slide 43 advances, the stud 526 moves away from the blade 525, which is then forced outward from the assembling channel (see Fig. 6) by the direct contact of the slide therewith.

When the slide 43 transfers the assembled line to the casting position, as in the previous patent, it contacts with and swings the depending arm 88, and thereby operates the jaw 84 to confine the rear end of the line. This movement of the arm 88 also effects the starting of the automatic machine operations, but in a slightly-different manner from the one previously described. The starting-bolt 93 (see Fig. 5) no longer rests directly upon the sector 91, but is held in its inoperative position by the pawl 647, (see Figs. 1, 2, and 7,) which is normally pressed by the spring 648 into engagement with the shoulder 649 of the handle 428. As the arm 88 swings inwardly the sector 91 is moved outwardly, and the arm then contacts with the pawl 647 and releases it from its engagement with the shoulder 649, where-

upon the spring 430 advances the lever 425 and starts the automatic operations. At this time the bolt 93 moves inwardly past the shoulder 92 of the sector 91, (see Fig. 11,) and the jaw 84 is thus locked in operative position until the retraction of the parts, when the pawl 647 again engages with the shoulder 649. Although no longer in direct contact therewith, the sector 91 acts, as in the previous patent, to prevent the forward movement of the bolt 93 and the initiation of the automatic operations in the event of an overset line. The depending arm 88 (see Figs. 2 and 7) is U-shaped to permit the opening of the pivoted gate 522, forming one side of the assembling-channel I. (See also Figs. 5 and 6.)

When the line has been transferred to the casting-point, it enters and is contained partly within the spacer device J. (See Figs. 8, 9, 10, and 17^a.) The ears B, B' of the spacers B enter the grooves J, J' of the device or elevator J and are supported thereby. The matrices A, while contained within the elevator J, are nevertheless free therefrom, being supported by the engagement of the ledge 82 with one side of the matrix and of the bar 83 with the lower opposite corner thereof. (See Figs. 8 and 9.) In this position one side of the device J also rests upon the ledge 82 and is sustained thereby. A projecting lug 79 of the device J (see Figs. 17, 17^a, 18, 18^a; and 32) constitutes the front jaw or abutment for the line. In place of the pivoted device presented in the former patent a vertically-movable elevator J is herein employed, mounted to slide upon the guide 533. (See Figs. 1, 2, 3, 4, 7, 17, 18 and 32.) The necessary motion is imparted to the device J by the helically-grooved cam 532 on the vertical shaft 126, which engages with a roller on the cam-arm 530, one end of which is pivoted at 531 to the machine-frame and the other end of which passes between the roller 534 and the stud 535 on the spacer-elevator J. The cam 532 is loosely mounted upon the shaft 126, but is detachably connected thereto by the key 536. (See Figs. 2 and 7.) This detachable connection permits the casting of a plurality of slugs from the same assembled line, which will remain in proper position therefor within the device J so long as the connection between the cam 532 and the operating-shaft 126 is broken.

After the slug is cast through the parts described the elevator J rises to the position shown in Figs. 18, 18^a, and 49, thus removing the spacers B from the line and lifting the front jaw 79 from before the matrices A, which may now be transferred to their elevating means. The elevator J is provided with a slide 540, which normally stands at the entrance to the elevator, but is moved toward the jaw 79 in front of the assembled

line as it is transferred thereto and holds it in close order. When the device J assumes its uppermost position, (see Figs. 17^a, 18, 18^a, and 49,) the slide 540 is moved in the direction of the arrows by the contact-piece 542, thereby pushing the spacers B before it and restoring them to the spacer-magazine G. The contact-piece 542 is provided with a spring-pressed plunger 541, which in the event of a jam or the displacement of parts yields sufficiently to obviate breakage, &c. The means for imparting the necessary motion to the contact-piece 542 will be subsequently described.

15 After the device J has lifted the spacers and the front jaw from the casting position the remaining matrices A are then transferred to the elevator-bar 580 by the longitudinally-movable rod 547, (see Figs. 1, 2, 7, 20, 17, 18, and 19,) which is arranged above and at one side of the line-channel and is provided with a depending pivotally-mounted finger 548, normally pressed laterally by the spring 549 against the side of the channel and 25 out of the way of the line as it is transferred to the casting-point. When the device J has assumed its upper position, the rod 547 is moved longitudinally, and the finger 548 contacts with the bevel 550 (see Fig. 18) at the 30 end of the ledge 82, thus bringing the finger into position to engage the matrices and in the further movement of the rod 547 to transfer them to the elevator-bar 580. The necessary motion is imparted to the rod 547 by the 35 oscillation of the mold-frame K, which is provided with a pin 554, engaging loosely in a hole in the end of the connecting-rod 551. The pin 554 is of sufficient length to permit the movement of the mold 100 to and from 40 the presented line without disengaging it from the connecting-rod 551. As the oscillating movement of the mold-frame K is somewhat greater than required for the purpose of actuating the rod 547, it is necessary 45 to provide the lost-motion connection 552, which consists of a spring-pressed stud mounted upon the rod 547 and engaging a slot in the connecting-rod 551. The connecting-rod 551 (see Fig. 7) is of reduced 50 thickness for a portion of its length, thus permitting the movement of the connecting-rod 551 without actuating the rod 547 until its corner 553 reaches the stud 552. At this point the spring-pressure of the connection 552 is increased sufficiently to compel the simultaneous operation of the rod 547 with the connecting-rod 551 during the remainder of the movement of the latter, and the consequent transferral of the matrices A by the 55 finger 548 to the elevator-bar 580. It is to be noted that the slot in the connecting-rod 551 (see Fig. 18) extends practically to the end thereof and substantially beyond the corner 553. This arrangement, due to the 60 yielding connection 552, permits a slip be-

tween the parts in the event of the matrices becoming jammed.

The contact-piece 542, which operates the slide 540 to transfer the spacers B from the device J to their magazine G, is operated from the rod 547 at its rear end (see Fig. 19) is formed with a recess 562, in which a rack 561 is mounted to slide. The rack 561 meshes into the pinion 560, suitably mounted upon the machine-frame, and the pinion 560 engages a rack 559, formed upon the lower side of the longitudinally-movable rod 558, which is connected by the link 543 to the contact-piece 542. When the device J is in its lowermost position, (see Fig. 17,) the contact-piece 542 is at the extreme end thereof in proximity to the jaw 79. As the elevator rises the piece 542 is drawn partially, but not completely, across it by the link 543, connected to the rod 558. At this time the rod 547 begins its operation, but without moving the rack 561 until the end of the recess 562 contacts therewith. The rod 547 then continues its operative movement, carrying the rack 561 with it, and through the pinion 560, rack 559, rod 558, and link 543, completing the traverse of the contact-piece 542 across the spacer device J to the position shown in Figs. 18, 18^a, and 49, and thereby transferring the 95 spacers B therefrom to the magazine G. The reverse movement of the mold-frame K and link 551 afterward restores the connected parts to their original positions.

After the matrices have been moved to the elevator-bar 580, they are conveyed thereby along the bar N by the endless chain M to the distributing devices at the top of the machine. (See Figs. 1, 3, 4, 17, 18, 32, 33, 34, 35, 36, 37, 38, and 39.) The elevator-bar 580 is mounted in proper position upon the frame 579, which slides upon the bar N. The endless chain M passes at its lower end around the sprocket-wheel 570, suitably mounted on the machine-frame, and at its upper end around the sprocket-wheel 571, journaled on the end of the bar N. Connected to the sprocket-wheel 571 is a gear 572, arranged in proximity to the pinion 573 upon the constantly-rotated shaft 644. (See Fig. 32^a.) The bar N is capable of a slight longitudinal movement sufficient to engage the gear 572 with the pinion 573, and thereby to actuate the chain M in the manner subsequently to be described. The chain M is connected by a link 575 to a nut 576, loose on the bolt 581. The bolt 581 passes through and is connected to the elevator-frame 579 at its two ends, and between the nut 576 and the frame 579 two spiral springs 577 and 578 are interposed, thus providing for a yielding connection between the link 575 and the elevator-frame 579. (See Fig. 32.) The object of this yielding connection is to insure absolute accuracy in locating the bar 580 in its operative positions at opposite 125 130.

ends of its path without elaborate machining and fitting, and to preserve this accuracy at all times during the life of the machine. In other words, a certain amount of over-motion is provided for; but the yield of the springs 577 and 578 permits the elevator-bar 580 to come to a fixed seat, both in its lower position, as shown in Fig. 32, and in its upper position, as shown in Fig. 38.

10 The longitudinal movement of the bar N, which engages the gear 572 with the pinion 573, and thus causes the actuation of the chain M, is secured by the lever 585 on shaft 586, the outer end of which abuts against the lower end of the bar N. The shaft 586 is provided with an arm 587, (see Figs. 7 and 32,) which connects with the slide 588, and thereby with the pivoted lever 591. The cam 180 on the shaft 126 has a stud 589, (see also Fig. 32^b,) which is so arranged as to engage the lever 591 at the proper time and through the parts described turn the shaft 586 and the lever 585 to move the bar N longitudinally so as to mesh the gear 572 with the pinion 573.

15 In order to maintain the bar N in its uppermost position after the stud 589 has passed out of engagement with the lever 591 and until the elevator 780 has completed its return journey, a locking-pawl 590 is provided.

20 The pawl 590 is formed with a locking-notch 593 to engage one end of the lever 585 and is normally pressed upward by the spring 592. When the lever 585 is operated to move the bar N longitudinally, its farther end passes

25 downward and engages the notch 593 of the spring-pressed pawl 590, thus holding the lever 585 in its operative position (see Fig. 2) until the return of the elevator, at which time the bolt 581 strikes a stud 594 upon the

30 pawl 590, tripping the latter and permitting the turning of the lever 585 and the descent of the bar N, (see Fig. 32,) and the parts remain in these positions until the next revolution of the vertical shaft 126 again causes

35 them to operate as before. It will be seen that the lever 591 may, if desired, be operated manually for the same purpose.

When the elevator-bar 580 assumes its uppermost position, (see Fig. 38,) it remains

40 there long enough to permit the matrices A to be transferred therefrom to the stationary bar 606. This dwell is provided for by the fact that the bar 580 has come to a fixed seat and halts there during the time that the upper end of the link 575 passes over and around the sprocket-wheel 571, (see Fig. 39,) the spring 577 yielding sufficiently to permit the operation described. While the parts are in this position, the matrices A are shifted

45 from the elevator-bar 580 to the fixed bar 606 by the transfer-piece 600 on the bent rod 601. The construction and operation of these means are shown in Figs. 1, 3^a, 4, 33, 34, 35, 36, 37, 38, 39, and 40. The rod 601 is

50 mounted to slide in the upper portion of the

machine and is surrounded by a spiral spring 602, which acts thereon to force it into its innermost or operative position. The upward movement of the elevator, however, causes it to assume its outermost position (see Fig. 38) in readiness to engage the matrices on the elevator-bar 580 and transfer them to the fixed bar 606. A cord or flexible connection 603 is attached to the rod 601 and passes outwardly around the pulley 604 to the upper portion of the slide or piece 605, which is contained within a longitudinal recess 610 in the bar N. In its lowermost or normal position the slide 605 occupies all of the recess 610 except a small portion at the bottom thereof, as clearly shown in the drawings. The nut 576 is provided with a depending pivoted pawl 611, (see Figs. 32, 36, 37, and 37^a,) which projects through a slot in the plate 614 of the elevator-frame and normally rests upon the upper surface of the bar N. As the elevator moves upwardly and reaches the position shown in Fig. 36, the pawl 611 passes down the lower bevel-surface of the recess 610 and engages the end of the slide 605. The elevator continues to rise until it assumes its uppermost position, (see Fig. 37,) carrying the slide 605 before it, and through the cord 603 shifting the bent rod 601 and transfer-plate 600 to its outermost position. (See Fig. 38.) As before explained, the elevator-bar 580 at this time comes to a fixed seat, but the chain M continues its movement, compressing the spring 577 and advancing the nut 576 on the bolt 581 relatively to the elevator-frame 579. This additional movement of the nut 576 causes the engagement of the bevel-ears 612 612 (see Fig. 37^a) of the pawl 611 with the bevel cam-surfaces 613 613 on the plate 614 of the elevator-frame, and thus lifts the pawl 611 out of engagement with the end of the slide 605.

In order to prevent the too rapid return of the slide 605 by the cord 603 and the spring 602 and to obtain an easier and more deliberate action of the transfer-piece 600 upon the matrices A, the slide 605 is provided with a retarding-blade 615, formed with an incline or cam-surface 616 and a shoulder 617. At the time when the pawl 611 is freed from engagement with the slide 605 the upper end of the connecting-link 575 comes into contact with the lower end of the blade 615, and thus prevents the immediate return of the slide 605. (See Figs. 36, 37, 38, and 39.) As the chain M continues its movement, (see Fig. 39,) the upper end of the link 575 comes into contact with the inclined cam-surface 616, (position a,) and as it passes around the sprocket-wheel 571 it engages with successive portions of the cam-surface 616, thus permitting the blade 615, the slide 605, and the connected parts to return at a deliberate and regular speed. The upper end of link 130

575 thus passes entirely along the cam-surface 616 until it is engaged by the shoulder 617, (position *b*.) The shoulder 617 then rests upon the upper end of the link 575, and 5 the blade 615, the slide 605, and the connected parts resume their normal positions as the chain continues its downward course, (position *c*.) It will be noted (see Fig. 36) that the lower bevel end of the recess 610 in the 10 bar N permits the pawl 611 to ride thereon and resume its normal position upon the upper surface of the bar N.

After the matrices A have been transferred to the stationary bar 606 the tension of the 15 spring 602, acting through the bar 601 and transfer-piece 600, presses them into position against the guiding-piece 625, to be elevated one by one to the distributing-bar Q and chain P. These devices are illustrated in 20 Figs. 3^a, 4, 35, 40, 41, 42, and 43. The grooved cam 623 upon the constantly-rotating shaft 624 acts upon the lever 622 to reciprocate the slide 621 and the lifting-piece 620 connected thereto. The piece 620 is located 25 within the guide-piece 625 in place to lift the extreme matrix on bar 606 as it is pressed into position by the transfer-piece 600, previously described. The nose or projection 630 on the end of bar 606 engages the 30 inclined slot A¹⁰ of the matrix A, (see Fig. 10^a,) so as to move the matrix laterally during its ascent and to prevent more than one from being lifted at a time by friction or otherwise. The lifting-piece 620 raises the matrix 35 away from the guide 625 to the position shown in Fig. 43, where it is held by the leaf-spring 628 in exact registration with the distributor-bar Q. (See Fig. 42.) As an additional precaution on the opposite side of the 40 matrix from the leaf-spring 628 a pawl 626 is provided, which is normally projected into the path of the rising matrix by the spring 627. During its elevation the matrix forces the pawl 626 inwardly until the pawl passes 45 beneath its ear in position to engage it, if necessary. (See Fig. 43.) The matrix is now in place to be engaged by the chain P and carried along the bar Q, from which it is dropped into its appropriate channel in the 50 magazine C in the manner well understood in the art. The chain P and its actuating devices are shown in Figs. 1, 2^a, 4, 33, 34, 35, 38, 44, 45, 46, 47, and 48. As in the previous case the endless chain P is composed of a 55 series of links P', mounted at one end upon the sprocket-wheel 168 on shaft 163 and at the opposite end on sprocket-wheel 170 on shaft 169. The links P' are formed with depending projections or straight edges 171 171 60 and straddle and rest upon the bar Q (see Figs. 38 and 44) in the same manner as described in the previous patent. In order, however, to increase the carrying capacity of the chain, each link is formed with two 65 straight edges 171 171 instead of one. The

straight edges 171 171 are perpendicular to the line of travel and engage the side of the matrices suspended from the bar Q throughout a considerable portion of their length, and thus prevent vibration or swinging of the 70 matrices during their journey. Each link P' is also provided with a short straight edge 172, (see Fig. 38,) parallel to and abutting against a straight edge 171 of the next link P', and so on throughout the series, thus insuring the parallelism of all the straight edges 75 171 171 and their perpendicularity to the line of travel.

Motion is imparted to the chain P by the sprocket-wheel 170 on the shaft 169, which 80 is actuated by the worm-gear 633 thereon meshing into the worm 634 on the constantly-rotated shaft 624. (See Figs. 45, 46, 47, and 48.) In order to afford a yielding connection to permit the arrest of the chain 85 P in the event of a jam or other interruption to its progress, the worm-gear 633 is loosely mounted upon the shaft 169 and engages a spring-pressed plunger 636, projecting from the arm 635, rigidly secured on the shaft 169. 90 The worm-gear 633 at its side is formed with a series of depressions 637, having bevel sides with which the spring-pressed plunger 636 is adapted to engage. In the event of an interruption or strain the head of the plunger 95 636 will ride up and along the bevel sides of the depression 637, and thus arrest the movement of the chain. If the interruption continues, the clattering caused by the engagement of the plunger 636 with the successive recesses 637 637 will give notice to the operator of a derangement. It will be noticed in Fig. 45 that the several recesses 637 637 bear an exact relation to the teeth of sprocket-wheel 170. This insures the synchronous actuation 100 of the chain P and matrix-lifter 620, which is operated, as previously described, from the shaft 624.

Motion is imparted to the devices at the upper portion of the machine by pulley 380 110 on sleeve 369, belt 381, and pulley 640 on the transverse shaft 624. (See Figs. 1, 2, 4, 33, 34, and 35.) On the shaft 624 (see Figs. 34 and 35) are mounted the worm 634 for actuating the chain P' and the cam 623 for actuating the matrix-lifter 620, both previously referred to, and also the sprocket-wheel 641, which by the sprocket-chain 642 and sprocket-wheel 643 imparts motion to the shaft 644 and pinion 573, whereby the matrix-elevating mechanism and connected parts are operated.

The means for conveying the finished slug to the galley Y and for shifting it therein are shown in Figs 1, 4, 7, 28, 30, and 32. When the slug Z is ejected from the mold 100 by the blade S, it drops into a chute 652, provided with inclined sides, so as to change the position of the slug as it passes therethrough into the galley Y. After it is delivered in the 130

galley it is necessary to advance it, together with the slugs previously deposited, so as to make room for the next in series, and this is effected by the vibrating piece 653, connected to the lever 654. A reciprocating movement is imparted to the lever 654 by the finger 342, (see Fig. 30,) which is actuated by the spring 345 in one direction and by the knife-operating rod 312 in the opposite direction, as described in the previous patent. The galley Y is provided with a movable piece 655 to engage the opposite end of the series of slugs while they are being advanced by the-vibrating piece 653.

15 Having thus described my invention, what I claim, and desire to secure by Letters Patent of the United States, is as follows:

1. In a typographic machine, the combination with a spacer-magazine of the spacers 20 therein, the said spacers having their upper ends unconfined and their lower ends resting against an abutment, together with an escapement to lift them clear of the abutment.

2. In a typographic machine, the combination with a spacer-magazine of the spacers 25 supported therein, the said spacers having their upper ends inclined inwardly from the front of the magazine.

3. In a typographic machine, the yielding 30 resistant comprising a movable rod, a finger thereon to confine the line, and a stud thereon to engage a groove so as to shift the finger into and out of the path of the line.

4. In a typographic machine, the yielding 35 resistant comprising a movable rod, a finger thereon to confine the line, and a stud thereon to engage a groove so as to shift the finger into and out of the path of the line, the said groove being formed with a straight portion 40 and an inclined portion for the purpose named.

5. In a typographic machine, the yielding 45 resistant comprising a movable rod, a finger thereon to confine the line, a stud thereon to engage a groove so as to move the finger into and out of the path of the line, and a spring connected to the rod and normally tending to turn it.

6. In a typographic machine, the combination 50 of a movable resistant, a suitably-actuated transfer-slide, and a device thereon to engage with the resistant and restore it to its normal position.

7. In a typographic machine, the combination 55 of a movable resistant, a suitably-actuated transfer-slide, a device thereon to engage the resistant and restore it to its normal position, and means to engage and disengage the said device and the resistant.

8. In a typographic machine, a vertically- 60 acting support for the matrices at the assembling-point, combined with automatic means to throw it into and out of operative position.

65 9. In a typographic machine, a movable

vertically-acting support for the matrices at the assembling-point, combined with the transfer-slide and operated thereby.

10. In a typographic machine, the combination of a line-transfer device, a line-confining jaw movable into the path of the line, and independent starting means, the said jaw and starting means being both actuated by the transfer device. 70

11. In a typographic machine, the combination of starting means, a line-confining jaw controlling the same whereby the starting of the machine is prevented unless the line be properly confined, and an independent device for tripping the starting means. 75

12. In a typographic machine, and in combination with casting mechanism, a device movable on vertical ways to remove the spacers from the line at the casting-point.

13. In a typographic machine, and in combination with a spacer-magazine, a device movable on vertical ways to remove the spacers from the line at the casting-point, and further means to restore them to the magazine. 85

14. In a typographic machine, and in combination with casting mechanism, means to receive the line at the casting-point, the said means being provided with a slide which retreats before the line as the latter is transferred thereto, together with mechanism to restore the slide to its normal position and eject the spacers from the receiving means. 90

15. In a typographic machine, the combination of a suitably-actuated movable mold 100 and matrix-transfer devices connected thereto and operated thereby.

16. In a typographic machine, the combination of a suitably-actuated movable mold and spacer-transfer devices connected thereto and operated thereby. 105

17. In a typographic machine, the combination of a suitably-actuated movable mold with matrix-transfer devices and spacer-transfer devices, both connected to and operated by the mold. 110

18. In a typographic machine, the combination of a suitably-actuated movable mold with matrix-transfer devices and spacer-transfer devices, both connected to the mold 115 and operated thereby in opposite directions.

19. In a typographic machine, the combination of spacer-transfer devices with operating means therefor, the said operating means including a rack and pinion, the rack remaining inoperative during a part of the operation 120 in order to secure lost motion.

20. In a typographic machine, the combination of an elevator to receive and hold the matrices with a suitably-operated endless 125 chain connected thereto whereby the continuous movement of the chain effects the reciprocation of the elevator.

21. In a typographic machine, the combination of a reciprocating member, a stop 130

therefor, and an actuating-chain, together with a yielding connection between the chain and the member.

22. In a typographic machine, the combination of an elevator, operating means therefor, and a longitudinally-movable guiding-bar on which the elevator travels, the movable bar being constructed and arranged to control the operating means.

10 23. In a typographic machine, the combination of an elevator, a suitably-operated chain to actuate the elevator, and a longitudinally-movable guiding-bar on which the elevator travels, the movable bar being constructed and arranged to control the operating means.

20 24. In a typographic machine, the combination of an elevator, operating means therefor, and a longitudinally-movable guiding-bar on which the elevator travels, the movable bar being constructed and arranged to control the operating means, together with mechanism to move the bar longitudinally.

25 25. In a typographic machine, the combination of an elevator, operating means therefor, and a longitudinally-movable guiding-bar on which the elevator travels, the movable bar being constructed and arranged to control the operating means, together with mechanism to move the bar longitudinally and additional means for locking the said mechanism in position during the movement of the elevator.

30 26. In a typographic machine, the combination of an elevator, operating means therefor, and a longitudinally-movable guiding-bar on which the elevator travels, the movable bar being constructed and arranged to control the operating means, together with mechanism to move the bar longitudinally and additional means for locking the said mechanism in position until the elevator returns and contacts therewith.

35 27. In a typographic machine, the combination of an elevator and operating means therefor comprising an endless chain, which provide for an over motion, together with a fixed seat for the elevator in its operative position.

40 28. In a typographic machine, the combination of an elevator, operating means therefor, comprising an endless chain, and connections between the elevator and its operating

means which permit a yield longitudinally of the elevator's path, together with a fixed seat 55 for the elevator in its operative position.

29. In a typographic machine, the combination of an elevator, operating means therefor, comprising an endless chain, and connections between the elevator and its operating 60 means, the said connections comprising a spring which permits a yield longitudinally of the elevator's path, together with a fixed seat for the elevator in its operative position.

30. In a typographic machine, the combination of elevator mechanism, means for transferring the matrices therefrom and operated thereby, and further means to retard 65 the transfer.

31. In a typographic machine, the combination of elevator mechanism, spring-actuated means for transferring the matrices therefrom and controlled thereby, and separate means to retard the transfer.

32. In a typographic machine, the combination of elevator mechanism, a slide actuated by the elevator mechanism, spring-actuated means for transferring the matrices from the elevator connected to and controlled by the slide, and a device also connected to 80 the slide to contact with the elevator mechanism and retard the transfer.

33. In a typographic machine, the combination of means for lifting a matrix to the distributing position with a spring to bear upon 85 the matrix and hold it therein.

34. In a typographic machine, the combination of means for lifting a matrix to the distributing position with a pawl to engage the matrix and hold it therein.

35. In a typographic machine, the combination of distributing mechanism and devices for delivering the matrices thereto, together with connected operating means therefor, the said operating means comprising a yielding connection, which in its operative relation insures the proper synchronism of the parts.

In testimony whereof I have subscribed my name to this specification in the presence 100 of two attesting witnesses.

FRED EUGENE BRIGHT.
